US00D588907S

(12) **United States Design Patent**
Cesario, Jr.

(10) **Patent No.:** **US D588,907 S**
(45) Date of Patent: **** Mar. 24, 2009**

(54) **CONTAINER**

(75) Inventor: **Sal Cesario, Jr.**, West Linn, OR (US)

(73) Assignee: **Paccess Incorporated**, Portland, OR
(US)

(**) Term: **14 Years**

(21) Appl. No.: **29/291,550**

(22) Filed: **Sep. 5, 2007**

(51) **LOC (9) Cl.** **09-03**

(52) **U.S. Cl.** **D9/418; D9/424; D9/432**

(58) **Field of Classification Search** **D9/430-433, D9/414-418, 420-429, 560, 561; D3/201, D3/273, 294, 302, 315, 317; 206/278, 454, 206/457, 772, 775-778, 781-783, 822; 229/93, 229/100, 103.3, 104-106, 108, 108.1, 109, 229/110, 111, 112, 115, 120, 125.015, 162.1, 229/162.3-162.7, 182.1, 215, 247, 406, 407, 229/902, 920, 922, 930, 942; D6/634; D19/75**

See application file for complete search history.

(57) **CLAIM**

I claim the ornamental design for a container, as shown and described.

DESCRIPTION

FIG. 1 is a top, left side perspective view of the front side of a container illustrating my new design;

FIG. 2 is a left side thereof;

FIG. 3 is a right side thereof;

FIG. 4 is a bottom view thereof;

FIG. 5 is a back side view thereof;

FIG. 6 is a top view thereof; and,

FIG. 7 is a front view thereof.

The broken lines represent the portions of the design that form no part of the claimed design.

1 Claim, 2 Drawing Sheets
